H. A. JUNG

BEAM COMPASS

Filed Feb. 14, 1927

INVENTOR
HARRY A. JUNG.

BY *Philip S. Hoffmann*
ATTORNEY

UNITED STATES PATENT OFFICE.

HARRY A. JUNG, OF BINGHAMTON, NEW YORK.

BEAM COMPASS.

Application filed February 14, 1927. Serial No. 168,029.

My invention relates generally to compasses and particularly to that type known as a beam compass which will permit the drawing of enlarged circles and arcs. The 5 principal object of my invention is to provide such a compass which is readily adjustable as to length and which is frictionally held in its adjusted position.

Another object is to provide novel pencil 10 and point or other instrument holding means, adjustable with respect to the compass proper and which are frictionally held in their adjusted positions.

A still further object is to provide such a 15 compass which is readily extendable for working with large diameters and which is likewise easily collapsed for use with comparatively small diameters.

A still further object is to provide a compass 20 of the character described which is of few parts, easily and cheaply constructed and assembled.

My improved compass is especially useful 25 in architectural drawing work as well as for carpenters and other draftsmen who work with large diameters.

Other objects and advantages in details 30 of construction and operation will be apparent as the description proceeds, reference now being had to the figures of the drawing wherein like reference numerals indicate like parts.

Figure 1 is a perspective view of my improved compass assembled and ready for use, 35 the length of the compass being broken.

Figure 2 is a detail cross section taken on the line 2-2 of Figure 1.

Figure 3 is a detail end view of the compass 40 illustrating clearly the frictional adjusting means of the instrument holder.

Figure 4 is a detail top plan view of a modified form of pencil holder.

Figure 5 is a side view thereof.

Figure 6 is a side view of the compass 45 shown in Figure 1 illustrating a method of providing for an extra extension thereof.

Figure 7 is a view of a modified compass in its collapsed position.

The body of my improved compass 50 comprises the two telescoping channel members 1 and 2, the latter fitting within the former and slidable therein to adjust the length of the sections. These sections may be formed to provide a close frictional fit, one within

the other, whereby they may be extended 55 or adjusted with respect to each other readily but with sufficient frictional resistance to retain the sections in adjusted positions.

The ends of the sections 1 and 2 are open and in the end of section 1 there is slidably 60 fitted, a supporting member 3, in this instance comprising a flat plate slidable within the channel 4 of section 1, and provided centrally with a resilient tongue 5 preferably struck or formed from the material of 65 the support 3. This resilient tongue 5 is adapted to engage against the wall 6 of section 1 whereby to retain the support in its adjusted position within the section.

It will be noted that the wall of section 1 70 opposite the wall 6 is left open as at 7. The support 3 is provided at its outer end with an extension 8 extending at an angle thereto notched as at 9 to permit the support 3 to be adjusted longitudinally of the section 1 75 without interference with the flanges 10 of the section. The free end of the portion 8 is preferably bent to form a resilient cylindrical holder 11 within which is adapted to be frictionally held the point member 12 of 80 the compass.

There is thus provided a novel holder for 85 the compass point, pencil, pen, or other instrument which is of one piece construction and which may be readily adjusted within the section and frictionally retained in its adjusted position. The provision of the resilient tongue 5 permits the operator to press inwardly on the supporting plate 3 thus relieving the friction between such plate 90 and the overhanging walls 10 of the section whereupon the holder may be readily slid in or out with respect to the section and upon release of the supporting plate 3, the tongue 5 will force the same back into engagement with the overhanging flanges 10 thereby restoring the friction between the supporting plate 3 and such flanges to retain the holder in adjusted position.

The same construction as described in connection with the end of section 1 of the compass is provided for the end of section 2 and need not be repeated. The same reference characters refer to the same parts and the holders are identical in construction and may be substituted one for the other. It is understood, of course, that in the holder at the end of section 2, a pencil 13 is provided 100

instead of the point 12. These may be interchanged, however, as desired. It will be also understood that a ruling pen or other instrument may be substituted for the pencil 13 if desired.

In Figures 4 and 5, I have illustrated a modified form of holder comprising a supporting plate 14, resilient tongue 15 and notched angular portion 16, these parts being identical with the parts 3, 5 and 8 of the modification just described. In this form however, the free end of the angular extension 16 instead of being bent upon itself to form a clip or resilient cylinder for receiving the pencil 17, is left with a straight free edge over which is adapted to be frictionally engaged the resilient sleeve 18, split throughout its length along one side, whereby it may be frictionally clamped to the free 15 end of the angular extension 16, the pencil 17 in this case being clamped in the lower end of the sleeve 18.

In Figure 6, I have illustrated the compass sections 1 and 2 of the compass shown 25 in Figure 1, provided with an additional section 19 for providing greater length to the compass.

In Figure 7, I have illustrated a slightly 30 different arrangement of telescoping sections wherein a single outside section 20 is provided and into either end of which is frictionally slid the inner sections 21 and 22 carrying at their outer ends the holders 11.

From the foregoing, it will be clear that 35 I have provided an unusually inexpensive beam compass which may be formed of stamped metal or other suitable material and one which offers a wide field of use due 40 to the ready adjustability thereof. Of course, many changes may be made in details of construction and arrangement of parts without departing from the spirit and scope of my invention. I do not limit myself, therefore, to the exact form shown 45 other than by the appended claims.

I claim:

1. A compass comprising a member composed of telescoping sections frictionally adjustable one upon the other, and removable

instrument holders frictionally held in said sections.

2. A compass comprising a member composed of telescoping channel sections frictionally adjustable one upon the other, and removable instrument holders frictionally adjustable therein.

3. A compass comprising a member composed of telescoping channel sections frictionally adjustable one upon the other, and one piece removable instrument holders adjustable therein.

4. A compass comprising a member composed of telescoping channel sections frictionally adjustable one upon the other, one piece removable instrument holders adjustable therein, and means on said holders for frictionally holding an instrument.

5. A compass including a channel section, an instrument holder therein comprising a plate 70 slidable in said section, resilient means on said plate for frictionally holding said plate in adjusted position, an extension on said plate extending at an angle thereto, and an instrument holding member on said extension.

6. A compass including a channel section, an instrument holder therein comprising a plate 80 slidable in said channel section, a resilient tongue struck from said plate and engageable with a wall of said section for frictionally holding said plate in adjusted position, an extension on said plate at an angle thereto, the free end of said extension being formed to frictionally receive an instrument.

7. A compass including a channel section, an instrument holder therein comprising a plate 90 slidable in said channel section, a resilient tongue struck from said plate and engaging with a wall of said section for frictionally holding said plate in adjusted position, means for releasing said friction while adjusting said plate, an extension on said plate angular thereto, said extension being notched to permit sliding movement thereof in said channel section, and the free end of said section being bent upon itself to form a resilient instrument holding element.

HARRY A. JUNG.
